(57) **CLAIM**

The ornamental design for a glucose strip, as shown and described.

DESCRIPTION

FIG. 1 is a top perspective view of a first embodiment of a glucose strip according to our new design;

FIG. 2 is a front elevational view of the embodiment shown in FIG. 1;

FIG. 3 is a rear elevational view of the embodiment shown in FIGS. 1-2;

FIG. 4 is a top plan view of the embodiment shown in FIGS. 1-3;

FIG. 5 is a bottom plan view of the embodiment shown in FIGS. 1-4; and

FIG. 6 is a side elevational view of the embodiment shown in FIGS. 1-5.

FIG. 7 is a top perspective view of a second embodiment of a glucose strip according to our new design;

FIG. 8 is a front elevational view of a second embodiment shown in FIG. 7;

FIG. 9 is a rear elevational view of a second embodiment shown in FIGS. 7-8;

FIG. 10 is a top plan view of a second embodiment shown in FIGS. 7-9;

FIG. 11 is a bottom plan view of a second embodiment shown in FIGS. 7-10; and,

FIG. 12 is a side elevational view of a second embodiment shown in FIGS. 7-11.

The broken lines are shown in the views for illustrative purposes only and form no part of the claimed design.
